LATCHABLE COVER STRUCTURE

Elwood W. Parker, Murfreesboro, N. C.

Application November 24, 1934, Serial No. 754,671

1 Claim. (Cl. 217—124)

This invention relates to a latchable cover structure for the open tops of portable containers, such as baskets or barrels, and has for its object to provide, in a manner as hereinafter set forth, a cover-structure having as a part thereof a combined reinforcing and coupling means for detachably securing the structure in closed position with respect to the open top of a basket or barrel.

10 A further object of the invention is to provide, in a manner as hereinafter set forth, a circular cover structure of the slatted type having one of its slats, disposed at the diametric center thereof, provided lengthwise with a reinforcing element having inherent parts of its ends coacting with a pair of keeper members disposed at diametrically spaced points of an open top basket or barrel for latching the cover structure in closure position with respect to the basket or barrel.

15 Further objects of the invention are to provide, in a manner as hereinafter set forth, which is simple in its construction and arrangement, strong, durable, of slatted form, compact, of arcuate contour in cross-section, thoroughly efficient in its use, readily secured to and released from an open top barrel or basket, and inexpensive to manufacture.

20 To the above ends essentially, and to others which may hereinafter appear, the invention consists of such parts and such combination of parts which fall within the scope of the invention as claimed.

In the drawing:

25 Figure 1 is a fragmentary view in vertical section of an open top container, showing the adaptation therewith of a cover-structure in accordance with this invention.

30 Figure 2 is a top plan view of the cover-structure secured upon the upper open end of a container.

35 Figure 3 is a top plan view of the cover-structure in non-attached position.

40 Figure 4 is a fragmentary view in vertical section and upon enlarged scale of the cover-structure and container coupled together and further illustrating a keeper in inactive position in dotted and full lines and in active position in full lines,

45 Figure 5 is a fragmentary view in side elevation and upon an enlarged scale of the cover-structure and container coupled together,

50 Figure 6 is a fragmentary view in plan and upon an enlarged scale showing the manner in which

an end terminal portion of the combined reinforcing and coupling element is formed, and

Figure 7 is a top plan view of a modified form of cover-structure.

With reference to Figures 1, 2, 4 and 5, an annular portable open top container is indicated at 8. The container includes a body part 9, an inner hoop 10 positioned against the inner face and having its top edge flush with the top edge of body part 9 and an outer hoop 11 positioned 5 against the outer face and having its top edge flush with the top edge of body part 9. The hoops 10 and 11 are suitably secured to body part 9. There is anchored to the upper portion of the container 8 at diametrically opposite points there- 15 of a pair of oppositely disposed bendable compressible keepers 12 of V-shaped contour. The keepers 12 extend laterally from the hoop 11 the necessary distance for obtaining a function to be hereinafter referred to. Each keeper 12 in- 20 cludes an anchoring part 13 and a latching part 14.

With reference to Figures 1 to 6, the cover-structure generally indicated at 15 includes an annular rim 16, a pair of spaced diagonally extending parallel slats 17, a pair of spaced diagonally extending parallel slats 18 which are disposed in an opposite direction with respect to the direction in which slats 17 are disposed, a slat 19 arranged over slats 17, 18 and a slat 20 ar- 25 ranged over and of greater length than slat 19. The several slats referred to have their ends ex- 30 tend beyond the outer side face of rim 16. The slat 19 is disposed at the transverse diametric center of hoop 16. The slat 20 is disposed at the 35 horizontal diametric center of the hoop 16. Each of the slats 17, inwardly adjacent to one end thereof, is secured by the spaced holdfast means 21, 22 to the top edge of the rim 16 at a point between zero and 90° of the latter. Each of the 40 slats 17, inwardly adjacent to the other end thereof, is secured by the spaced holdfast means 23, 24 to the top edge of the rim 16 at a point between 180° and 270° thereof. Each of the slats 45 18, inwardly adjacent to one end thereof, is se- cured by spaced holdfast means 25, 26 to the top edge of rim 16 between 270° and 360° thereof. Each of the slats 18, inwardly adjacent to the other end thereof is secured by spaced holdfast means 27, 28 to the top edge of rim 16 at a point 50 between 90° and 180° thereof. The slat 19, inwardly adjacent to the end 29 thereof, is secured by spaced holdfast means 30, 31 to the top edge of rim 16. The slat 19, inwardly adjacent to its end 32, is secured by the spaced holdfast means 55

33, 34 to the top edge of rim 16. The longitudinal median of slat 19 aligns with the 90° and 270° points of rim 16. The slat 20, inwardly adjacent to the end 35 thereof, is secured by spaced holdfast means 36, 37 to the top edge of rim 16. The slat 20, inwardly adjacent the end 38 thereof, is secured by spaced holdfast means 39, 40 to the top edge of rim 16. The longitudinal median of slat 20 aligns with 0° and 180° points of rim 16.

10 The slats 18 extend across the slats 17 between the transverse medians and the ends of the latter. The slat 19 extends across the slats 18 and its central part thereof closes the interstice 41 formed by the slats 17, 18 axially of the cover.

15 The slat 20 extends across the central part of slat 19. The slat 19 is secured to one slat 17 and one slat 18 by the spaced holdfast means 42, 43 which also act to secure a slat 17 and a slat 18 together. The slat 20 is secured to the other slat 17 and the other slat 18 by the spaced holdfast means 44, 45 which also act to secure the said other slats 17 and 18 together.

There is associated with the slat 19 a combined reinforcing and coupling element 46 formed from a length of bendable metallic material 47 of the desired gauge. The material 47 is bent and also twisted upon itself to provide said element 46 with a pair of reinforced end parts 48 terminating in a closed bendable loop 49 formed of a diverging outer portion 50 and a converging inner portion 51. The portion 50 of the loop which tapers towards the outer end of the latter is of greater length than the portion 51 which tapers towards the inner end of the loop. The portion 50 constitutes a compressing means for a purpose to be referred to. The portions 50 of the loops 49 project beyond the end edges 29, 32 of the slat 19. The element 46 at the inner ends of its twisted parts 48 is anchored to the slot 19, at the longitudinal median of the latter by the spaced holdfast means 52, 53.

With reference to Figures 1 and 2, the container 8, at its top, is formed at diametrically opposite points with a pair of upstanding inverted yoke-shape handles 54 through which extends the end portions of slat 20 when the cover-structure 15 is arranged in closure position relative to the container. When structure 15 is in the position just referred to the rim 16 will be arranged against the inner face of hoop 10, the ends of slats 17, 18 and 19 upon the top edge of hoop 11 and the loops 49 extended slightly beyond hoop 11. The latching parts 14 of the keeper members 12 are then passed upward through the tapered portions 50 of the loops 49 and bent outwardly and downwardly to the position shown in Figures 1, 4 and 5. The tapered portions 50 of the loops 49 will compress the sides of the latch-

ing parts 14 of the keeper members 12 together to set up a frictional latch or lock between the element 46 and keeper members 12. The latching parts 14 of the keeper members 12, when compressed, will be as shown in Figure 5. When the cover-structure 15 is latched or detachably connected to the container 8 the element 46 acts as a reinforcing means for slat 19.

The modified form of cover-structure 55, shown in Figure 7, is of the same arrangement as that shown in Figure 3 with the exception that the slats 56, 57 thereof, which correspond to the slats 19, 20 respectively, are of the same length and the slat 57 has secured thereto a combined reinforcing and coupling element 46 in the same manner as the slat 56. The holdfast means 58, 59 of structure 55 corresponds to and performs the same function as holdfast means 44, 45, but in addition, acts also for securing element 46 to slat 57. Otherwise than as stated the form shown in Figure 7 is the same as that shown in Figure 3. When cover-structure 55 is employed it is to be used in connection with four keeper members 12.

What I claim is:

A cover structure comprising a hoop, a pair of spaced parallel inner slats anchored inwardly adjacent their ends directly to the top edge of and disposed diagonally relative to the hoop, a pair of parallel outer slats having stretches of their length seated upon said inner slats and anchored inwardly adjacent their ends directly to the top edge of and disposed diagonally relative to said hoop, the said outer slats being extended in an opposite direction with respect to said inner slats, an inner single slat having its lengthwise median aligning with the horizontal diametric center of the hoop, said single slat having stretches thereof mounted on the said outer pair of slats and anchored inwardly adjacent its ends directly to the top edge of the hoop, an element formed from a length of bendable metallic material secured upon the outer face of said single slat at the longitudinal median of the latter and having each end in the form of a loop extended beyond the end edges of the single slat, an outer single slat disposed at right angles to said inner single slat, having its lengthwise median aligning with the transverse diametric center of the hoop and being secured inwardly adjacent its ends directly to the top edge of the hoop, the said outer single slat having a stretch thereof mounted on said element and spaced stretches thereof mounted upon the said outer pair of slats, spaced means for securing the inner single slat to the inner and outer pairs of slats, and spaced means for securing the outer single slat to the inner and outer pairs of slats.

ELWOOD W. PARKER.
